UNITED STATES PATENT OFFICE.

GEORGE H. SHEPHERD, OF PARIS, FRANCE.

DUMB-BELL.

SPECIFICATION forming part of Letters Patent No. 787,407, dated April 18, 1905.

Application filed March 31, 1904. Serial No. 200,896.

To all whom it may concern:

Be it known that I, GEORGE HENRY SHEPHERD, a citizen of the Kingdom of Great Britain, residing at No. 1 Rue Caumartin, Paris, 5 in the Department of Seine, France, have invented a new and useful Improved Dumb-Bell, of which the following is a specification.

The present invention relates to improvement in dumb-bells destined for physical exercises and having especially for their object to cause the pupil to grasp vigorously in his hands the bars or handles to which the weights are connected.

It is recognized in practice that the development of the muscles, both of the arms, of the wrist, and of the hand, is much more efficient when the dumb-bell is firmly grasped in the hand during the exercise. This result is obtained according to my invention by attaching a special bar to each of the balls of the dumb-bell. These two bars being brought together end to end or connected one to the other by a hinge or by a pivot must be grasped simultaneously in the same hand. The 25 weight upon each of the balls tends constantly to place the two bars of the same dumb-bell at a certain angle or to make them turn upon their point of contact. It follows that the hand is obliged to exercise an energetic and 30 continuous compression upon the handle containing the bars of the dumb-bell in order to maintain said bars during the exercises in line one with the other.

In the accompanying drawings I have illustrated different models of dumb-bells constructed according to my invention.

Figure 1 shows a dumb-bell with two bars articulated as prolongation the one of the other. Fig. 2 shows a dumb-bell of which 40 the two bars are articulated upon the same intermediate piece. Fig. 3 shows a dumb-bell with two independent bars which can swing the one upon the other and which are adapted to be maintained parallel the one with the other. Fig. 4 shows a dumb-bell with two articulated bars which hinge and which are adapted to be maintained parallel the one to the other.

The dumb-bell represented in Fig. 1 is obtained by dividing in the middle the bar of a dumb-bell of the ordinary construction. The

two halves of the dumb-bell thus comprise two bars A A', provided each with a ball BB', the ends E E' of these two bars A A' being joined end to end by means of a hinge C, as 55 shown. In order to make use of this dumb-bell, the hinged ends of the bars A A' are placed in the hand. It will be easily understood that the hand must grasp firmly the bars A A' to overcome the effect of the weight which tends 60 to draw down the balls B B' in order to maintain the bars A A' in line with one another.

In the dumb-bell shown in Fig. 2 the two bars A A' are articulated, by means of the respective hinges CC', to one and the other part 65 of an intermediate piece D, having the same section as the bars. This arrangement compels the hand to exercise a still more vigorous pressure upon the bars A A'. In fact, during the exercise the piece D occupies the 70 middle of the hand and absorbs the effort of some of the fingers, which obliges the user to distribute over the other fingers all the exertion necessary to maintain the bars A A' in position. Moreover, as the said bars are 75 pressed in the hand upon a shorter length it follows that the weight of the balls is more and more difficult to overcome in proportion as there is given more extension to the width of the piece D. 80

In Fig. 3 the two bars A A', having each their respective balls B B', are devised to be held parallel in the hand and that so that the point F, carried by the bar A, may be poised in the socket G on the bar A'. This arrangement permits the bars A A' to turn upon the point F, so that the hand which holds together these two bars must exercise a vigorous pressure on the one part in order that the only point of contact between the bars shall be the 90 pivot and on the other part to maintain these bars vigorously parallel in the same plane. The pivot F and the socket G can each be cast in one piece with the bars and balls, respectively, which carry them. The distance which 95 separates the axis of the pivot from the vertical axis of the ball B is equal to that which separates the axis of the socket from the vertical axis of the ball B'. Owing to this arrangement, it follows that when the two bars 100 A A' are united by the pivot this latter forms the center or hinge of the construction.

Fig. 4 shows a modification of the dumb-bell represented in Fig. 3. Here the union of the two bars is effected by the aid of a hinge. The concave part L of the hinge is attached by means of a screw M to the bar A, and the convex part N of the hinge is attached by means of a screw O to the bar A', the concave part L being capable of being screwed down or compressed over the convex part N for preventing the two bars from becoming detached. The free ends P of the parallel bars A A', forming the handles of the dumb-bells, (shown in Figs. 3 and 4,) are cut on the slant in order to permit the bars to turn without striking the balls.

These dumb-bells can be constructed of suitable materials, each bar with its ball being capable of being made of cast metal and in a single piece. I can also make the balls of metal and the bars of another metal or of wood. The bars may be covered with suitable handles of wood, leather, &c.

What I claim is—

1. A dumb-bell comprising two parts, each having a weight at its outer end, and a hinge 25 at the middle of the grip portion said hinge adapted to form the only connection between said two parts.

2. A dumb-bell formed in two parts, a convex piece attached to one of said parts, a concave piece attached to the other of said parts adapted to fit over said convex piece and hinge said parts together whereby they may swing the one upon the other and be maintained in a parallel position with regard to 35 each other, and a weight at the outer end of each of said parts.

In testimony whereof I have signed my name to this specification in the presence of two subscribing witnesses.

G. H. SHEPHERD.
